RECORD CARD

Evert F. Johnson, Oil City, Pa., assignor to The Pennzoil Company, Oil City, Pa., a corporation of Pennsylvania

Application November 8, 1947, Serial No. 784,912

2 Claims. (Cl. 101—127.1)

1 This application is a continuation in part of my copending parent application, Serial No. 777,203, filed October 1, 1947, which relates to apparatus for effecting systematized customer notification service, the apparatus including, inter alia, a mechanism (which forms the subject of my co-pending application, Serial No. 792,470) for applying an address and a postage stamp to a mailing piece and a record card cooperative with the mechanism and with the mailing piece. The term "mailing piece" is defined in my parent application, and herein, as comprehending postcards, pamphlets and folders to be directly stamped and addressed, and envelopes containing mail matter, each of which items has the usual spaces for the postage stamp and the address.

The invention relates to improvements in the record card, these being concerned with its normal use, qua record card, and also with its specific features of cooperation with the address and stamp applying elements of the aforesaid mechanism.

The objects of the invention are to enable the record card, in addition to its function as such, to cooperate mechanically with the mailing piece and with the address and stamp applying mechanism in the application of the address and postage stamp to the mailing piece and in the ejection or delivery of the unit comprising the record card and the mailing piece from the mechanism; and, with the record cards in normally filed relation, to provide full protection for the panel and also full protection against smearing, by ink adhering to the panel, of the record carrying surface of the adjacent record card.

An embodiment of the invention, in a form now considered preferred, is illustrated in the drawings wherein:

Figure 1 is a plan view of the record card, showing its several parts in extended relation.

Figure 2 is a plan view of the record card and associated mailing piece as inserted into operative relation to the address and stamp applying mechanism, such parts of the mechanism as are necessary for an understanding of the invention being shown in horizontal section.

Figure 3 is a perspective view of the record card with an associated mailing piece shown in broken lines, the record card and the mailing piece being shown in readiness for insertion in operative relation into the address and stamp applying mechanism.

Figure 4 is a front elevation of part of a drawer

element by which the address and stamp applying mechanism is supported.

Figure 5 is a side elevation of the same.

Figure 6 is a view in front elevation of the address and stamp applying mechanism as mounted within and supported by the drawer element, the hinged panel which forms a part of the front of the drawer element being shown in open position.

10 15 **16** **17** **18** **19** **20** The address and stamp applying mechanism A (Figure 6) is mounted within the drawer element 8 (Figures 4 and 5) of a cabinet (not shown herein). The mechanism A and the drawer element 8, shown and described in detail in my parent application, Serial No. 777,203, are shown and described herein only in such detail as will enable an understanding of the functional features of my improved record card and the features of correlation among it, the mailing piece and the address and stamp applying elements.

The drawer element 8 includes a front wall 11 and side walls 9. The mechanism A (which forms the subject of my co-pending application, Serial No. 792,470) includes a stamp applying device 181 of any suitable known construction (for example as shown in Patent No. 1,877,849, issued September 20, 1932) and an address applying device, the essential elements of which are upper and lower roller quadrants 192 and 193 mounted on shafts 194 and 195 respectively. The upper quadrant 192 is provided with a facing 196 of suitable absorbent ink carrying and applying material and is movable in relation to an inking roll 197 arranged in contacting relation above it and at the lower end of ink reservoir 198. The support for the stamp and address applying device consists of a vertically planar transverse plate 170 which carries a forwardly projecting horizontal shelf 173. A longitudinal shoulder 174 and a transverse shoulder 175 in right angular relation are formed upon the shelf 173, the shoulder 174 being parallel to the plate 170 and the shoulder 175 extending forward from the inner end of the shoulder 174. The shoulders 174 and 175 constitute an L-shaped positioning guide for the record card to insure its proper initial location in cooperative relation to the elements of the mechanism A. Access to the mechanism for the purposes of replenishing the ink, inserting a new roll of stamps and lubrication, is provided for by a hinged upper panel 12 which forms a part of the front wall 11 of the drawer element and carries a knob 177 by means of which it may be conveniently opened or closed, the panel 12 being shown in its normally closed

position in Figures 4 and 5 and in its open position in Figure 6.

The record card R with an associated mailing piece M, as later described in detail, is moved into cooperative relation with the elements of the mechanism A through a horizontal slot 178 in the front wall of the drawer element 8 and is partially ejected (by the quadrant rollers 192 and 193) through an angular slot continuation 179 in the vertical wall 9 at which the slot 178 terminates. The slot 178 is formed by cutting away the lower edge of the panel 12 and may be bounded by a U-shaped reinforcing frame 180, one element of which is attached to the panel 12 and the other element of which is attached to the upper edge of the section of the front wall 11 below the panel 12.

The record cards are functionally associated with corresponding "service" cards, illustration of which herein is unnecessary but which are shown and described in detail in my said parent application, Serial No. 777,203.

Each record card consists of two major (outer and inner) integrally connected sections 155 and 156 delimited by a common folding line 157 and having vertical blank columns headed by appropriate titles or captions and sub-divided horizontally to provide, for reference purposes, "squares" to be filled in by the clerk with pertinent data. The section 155 has at one end a coplanar projection 158 which bears the name of the customer. The apparatus of which the record card is an element may be used in any enterprise where systematized customer notification service is desirable. The record card, as herein shown, is assumed to be used in establishments which serve the needs of motor car drivers, i. e., garages, filling stations and similar establishments. Therefore the projection 158 also bears notations as to the identity of the customer's car, his car license number and other appropriate information. The service cards, above mentioned, are filed in pockets of the filing machine, illustration of which herein is unnecessary but which is shown and described in detail in my said parent application, Serial No. 777,203. The sections 155 and 156 have certain columns, e. g., the two vertical columns at the left side of the section 155, which provide for the recording of the numbers of the pockets in which corresponding service cards may be filed at a time contemporaneous with the last entry on the record card.

The projection 158 constitutes an identification tab which enables the convenient selection of the record card in the cabinet in which it may be filed and its convenient removal. The section 156 has a rectangular window 159 covered by a panel 160 of suitable stencil material. The section 159 also has at its upper end an extension 161 to which it is connected by a transverse folding line 162. The extension 161 is provided for the protection of the panel of stencil material, for the protection of the adjoining record card, for carrying any printed instructions which may be required, and for convenience in effecting the removal of the record card at the completion of its ejective movement by the address and stamp applying mechanism A. When the record card is in the filing cabinet the extension 161 is folded upon the section 156 in order to protect the stencil material from dust or smearing. The extension 161 preferably bears upon the face which becomes its inner face when the extension is folded a coating 163 of any suitable varnish occupying a suitable rectangular area, the purpose of which

is to prevent the extension 161 from adhering to the ink impregnated panel 160 and to prevent the ink adhering to said panel from seeping through the thin cardboard of which the extension 161 is composed and smearing the surface of the section 155 of the adjacent record card. In the folded relation of the parts the section 155 protects the opposite face of the stencil panel 160 against dust and smearing.

The upper edge of the section 155 may be regarded as marked off by a printed line 164 and the upper edge 165 of the section 156 and the folding line 162 coincide with the line 164 whereby, with the parts in folded relation, the projection 158 extends as a tab beyond the upper edge of the card. The section 156 at its lower edge and adjacent the folding line 157 has a cut-away portion which provides a recess 166.

The mailing piece has the usual spaces for the postage stamp and address. In the use of the record cards for the stamping and addressing of mailing pieces the sections 155 and 156 are folded one upon the other with the data bearing side of the section 155 exposed. The mailing piece is inserted between the sections 155 and 156 to the extent limited by its engagement with the meeting edges of the sections as connected along the folding line 157. In such insertion the stamp bearing portion of the mailing piece is located in registry with the recess 166, the edge portion of the mailing piece is located in contacting engagement with the meeting edges of the sections 155 and 156 (i. e., the folding line 157) and the address bearing portion of the mailing piece is located in registry with the panel 160.

The record card, with the mailing piece thus associated with it and with its extension 161 in projected relation, is then introduced into the address and stamp applying mechanism.

The record card includes a vertical column bearing the caption "Date" in which the dates of customer notification are entered in the appropriate squares by the clerk. The record card also includes a column bearing the caption "Contact description" in which the clerk enters an indication of the nature of the contact with the customer, i. e., mail, telephone or personal call and, in the usual event that the contact is by mail, an indication of the mailing piece or pieces sent to the customer, it being understood that the mailing pieces are severally identified by numbers, code words or other symbolic identification. For the purpose of adequate capacity several series of columns may be provided for the identification of the particular pocket of the filing machine in which the customer's service card is filed, for the entry of the date of customer notification and for an entry indicative of the particular customer contact. As shown, the outer section 155 bears two series of such columns and the inner section 156 bears a single series.

Let it be assumed that a customer is to be notified of service needed. His record card shows whether there has been any previous contact. The information supplied by the service and record cards, considered in combination, enables the clerk to determine the character of notification required and the identity of the particular mailing piece to be sent. The date of notification is then entered in the corresponding square of the "date" column and a description of the particular notification or "contact" is entered in the corresponding square of the "contact description" column. The mailing piece M is then inserted

between the folded sections 155 and 156 and the record card, with its extension 161 in projected relation, is inserted into operative relation to the mechanism A.

In such insertion the record card is moved through the slot 178 and upon the shelf 173 with its inner end edges in contact with the shoulder 175, and its projected extension 161 at the same time moved to the permissible extent into the slot 179. The insertion movement of the record card is continued until arrested by the shoulder 174. As set forth in detail in my said parent application, Serial No. 777,203, the record card, at the completion of its insertion movement, trips the actuating element 215 of a switch which controls the motor by which the device 181 and the roller quadrants 192 and 193 are operated. A marginal recess 208 is formed in the shelf 173 to accommodate the peripheral portions of the quadrants during their operative movement.

When the stamp has been applied by the device 181 the roller quadrants 192 and 193 are operated and during their movement athwart the recess 208 seize the record card and effect its lateral movement, that is to say, its movement in a path at a right angle to the path of its movement as manually inserted through the slot 178, the shoulder 174 providing a guide. In the course of the movement of the card by the roller quadrants the address is applied to the mailing piece by the cooperation of the roller 192 with the panel 160. The movement of the card is through the slot 179 and is an ejective movement, that is to say at its completion the card is in a partially ejected position in which the extension 161 may be readily grasped by the operator and the record card, together with its associated mailing piece, removed from the machine. Thereupon the mailing piece is removed from the card, the extension 161 is folded over upon the section 156 and the card is replaced in its filing cabinet. As filed the extension 161 protects the panel 160 against dust and smearing and also protects the section 155 of the adjacent card against being smeared by ink adhering to the panel. The section 155 also protects the opposite side of the panel 160 against dust and smearing. Since the panel is fully protected it will, at all times, pro-

vide a clean and clear address upon the mailing piece.

I claim:

- 5 1. A record card for filing reference and for cooperation with an address and stamp applying mechanism comprising integrally connected outer and inner sections delimited by a common folding line, the sections as folded upon one another being adapted to receive between them a mailing piece, having the usual stamp and address bearing portions with one of its edges abutting the folding line by which the sections are delimited, the inner section being provided at one end and adjacent the outer section with a recess through which the stamp bearing portion of the mailing piece is exposed, being also provided with a panel of stencil material so located as to be in registry with the address bearing portion of the inserted mailing piece, and being further provided at its opposite end with an integral foldable extension to which it is joined along a transverse folding line, the extension being projected when the record card is used in cooperation with the stamp and address applying mechanism and being folded upon the outer face of the inner section when the record card is used for the purpose of filing reference, and the outer section being marked off into entry spaces and a space for identifying data.
- 10 20 25 30 35 2. A record card as set forth in claim 1 wherein the transverse folding line coincides with the upper ends of the sections and the outer section is provided beyond its upper end with a projecting co-planar tab which provides the space for the identifying data.

EVERT F. JOHNSON.
